UNITED STATES PATENT OFFICE.

SAMUEL S. COLT, OF ORANGE, NEW JERSEY.

STAGING FOR BUILDINGS AND OTHER STRUCTURES.

1,423,308.

Specification of Letters Patent.

Patented July 18, 1922.

Application filed October 27, 1920. Serial No. 419,814.

To all whom it may concern:

Be it known that I, SAMUEL S. COLT, a citizen of the United States, residing at Orange, in the county of Essex and State of New Jersey, have invented certain new and useful Improvements in Stagings for Buildings and Other Structures; and I do hereby declare the following to be a full, clear, and exact description of the invention, 5 such as will enable others skilled in the art to which it appertains to make and use the same, reference being had to the accompanying drawings, and to characters of reference marked thereon, which form a part of this 10 specification.

This invention has reference to improvements in stagings or stanchions used by contractors or builders during the erection of structures of various kinds; and, the present 15 invention relates, more particularly, to a novel construction of staging, or the like, comprising a number of slidably or movably connected retaining members in the form of uprights or stanchions provided with means 20 for adjustably fixing said uprights or stanchions lengthwise by means of a wedging means, and against sidewise movement by an arrangement of aligning or paralleling bands or straps.

The present invention, therefore, has for 25 its principal object to provide a novel and simply constructed staging, comprising movably or slidably connected retaining members, uprights or stanchions, and in addition 30 with each pair of connected retaining members, uprights, or stanchions, means for adjusting said retaining members, uprights or stanchions and securing the same lengthwise in fixed positions, and also providing 35 in connection with each pair of retaining members, uprights or stanchions means for securing the same in alined relation and against sidewise movements.

Other objects of the present invention not 40 at this time more particularly enumerated will be clearly understood from the following detailed description of the same.

With the various objects of the present invention in view, the said invention consists, primarily, in the novel staging or stanchions provided with means for adjustably connecting the members of the same, and at the same fixing the said members rigidly in supporting relation; and, the said invention 45 consists, furthermore, in the general ar-

rangements and combinations of the various devices and parts, as well as in the details of the construction of the said parts, all of which will be more fully described in the following specification, and then finally embodied in the clauses of the claims, which are appended to and which form an essential part of the said specification.

The invention is illustrated in the accompanying drawings, in which:—

Figure 1 is a front view and Figure 2 a rear view of fragmentary portions of two of the connected members of the staging or stanchion.

Figure 3 is an edge view of the connected 70 members shown in said Figures 1 and 2; and Figure 4 is a transverse vertical sectional representation of the same.

Similar characters of reference are employed in the said above described views, to 75 indicate corresponding parts.

Referring now to the several figures of the drawings, the reference-characters 1 and 2 indicate fragmentary portions of two of the said connected members, said members being 80 usually made of wood, and showing as uprights and supports for the various stagings or scaffolds employed by contractors or builders in the erection of buildings, retaining walls, concrete floorings, and in fact 85 with structures of any kind. As shown, the said retaining member, upright or stanchion 1 may be provided with any suitable number of bolt-receiving holes, as 3, for the reception of a bolt, as 4, the respective end portions of which are provided with screw-threads 5 and 6, for the screwing thereon of suitable nuts 7 and 8, the said bolt also having preferably mounted thereon a number of washers, as 9, 10 and 11. As indicated in 90 the drawings, the washers are usually square, or are made of any other shape which will prevent turning of said washers when tightening the nuts 7 and 8, the said washers when tightening the latter, imbedding themselves in the wood of which the several members are usually constructed. It will be understood, however, that circular washers may be employed, if desired.

As shown there is rotatably or oscillatorily 105 mounted upon the above-mentioned bolt 4, and adjacent to the surface 12 of the upright or retaining member 1 a wedge-receiving member or element 13 which is usually made of wood, but which may also be made 110

of other suitable material, said member or element being formed with a straight or flat receiving surface, as 14, upon which may be suitably disposed a wedge 15 which is 5 adapted to be tightly driven home, between said surface 14 and the end-surface 16 of the other upright or retaining member 2, for any final adjustment of the said upright or retaining member 2.

10 As an extra precaution, although not in every case a necessity, to hold the adjustably connected members in alinement against movement sidewise, any desired number of holding or retaining bands 17 which are 15 made to embrace the connected portions of the uprights or members 1 and 2 may be employed, said bands being usually secured in place by means of nails 18, or other suitable fastening means, as shown in the several 20 figures of the drawings.

To increase the width of the said bands, and thereby to procure additional bearing surface, the said bands may be provided with bearing-strips or plates, as 19, which 25 are pivotally connected with said bands by means of pivot-studs 20, in the form of rivets, or the like, and whereby the said strips or plates 19 may be vertically disposed, as 30 shown in the drawings, when the members 1 and 2 are connected, and which may be turned horizontally out of the way, when the members 1 and 2 have been disconnected, as will be evident.

The operation of the device will be clearly 35 understood from an inspection of the several figures of the drawings, and any further description of the same is therefore deemed unnecessary.

While the invention is most simple, still I 40 am aware that some changes may be made in the general arrangements and combinations of the several devices and parts, as well as in the details of the construction of the said parts, without departing from the scope of 45 the said invention as set forth in the foregoing specification, and as defined in the clauses of the claims which are appended to the same. Hence, I do not limit my present invention to the exact arrangements and 50 combinations of the various devices and parts as described in the foregoing specification, nor do I confine myself to the exact details of the construction of the said parts, as illustrated in the accompanying drawings.

I claim:—

1. In a staging or similar structure, a pair of retaining members having portions arranged side by side, a bolt connected with one of said members, a wedge-receiving element oscillatorily mounted upon said bolt, 60 and a wedge disposed between said wedge-receiving element and the other retaining member for adjustment of said members. 55

2. In a staging or similar structure, a pair of retaining members having portions arranged side by side, a bolt connected with one of said members, a wedge-receiving element oscillatorily mounted upon said bolt, and a wedge disposed between said wedge-receiving element and the other retaining member for adjustment of said members, 65 combined with means connected with the overlapping portions of said retaining members for maintaining said members against movement sidewise out of alinement. 70

3. In a staging or similar structure, a pair of retaining members having portions arranged side by side, and means connected with one of said members and adapted to engage the other member for adjustment of 80 said members, combined with retaining bands in embracing relation with the overlapping portions of said retaining members, and bearing-plates pivotally connected with 85 said retaining bands for maintaining said members against movement sidewise out of alinement. 75

4. In a staging or similar structure, a pair of retaining members having portions arranged side by side, a bolt connected with 90 one of said members, a wedge-receiving element oscillatorily mounted upon said bolt, and a wedge disposed between said wedge-receiving element and the other retaining member for adjustment of said members, 95 combined with retaining bands in embracing relation with the overlapping portions of said retaining members, and bearing-plates pivotally connected with said retaining bands for maintaining said members against 100 movement sidewise out of alinement.

In testimony, that I claim the invention set forth above I have hereunto set my hand this 22nd day of October, 1920.

SAMUEL S. COLT.
